UNITED STATES PATENT OFFICE.

ERWIN H. EILER, OF ST. LOUIS, MISSOURI.

SPARK PLUG.

Application filed August 27, 1926. Serial No. 131,915.

This invention relates to new and useful improvements in spark plugs and has for its primary object to provide a plug wherein the wire attaching end of the main electrode is equipped with means to positively prevent the entire detachment of the wire binding screw from the electrode, necessitating the attachment of the wire by wrapping the same around the electrode which at most is 10 highly unsatisfactory.

The invention further aims to provide a means for preventing the entire detachment of the binding nut that is of such nature as to not materially increase the cost of manufacture of the plug insomuch as the same is extremely simple of construction and inexpensive of manufacture.

With the foregoing and other objects in view as the nature of the invention will be 20 better understood, the same consists of the novel form, combination and arrangement of parts hereinafter more fully described, shown in the accompanying drawing and claimed.

25 In the drawing wherein like reference characters indicate corresponding parts throughout both the views.

Figure 1 is a fragmentary elevation of a spark plug constructed in accordance with 30 the present invention.

Figure 2 is a detail vertical section thereof, and

Figure 3 is a group perspective disclosing the upper end of the plug main electrode together with the means for preventing the 35 entire detachment of the binding nut therefrom prior to the permanent association of said means with said electrode.

Now having particular reference to the 40 drawing, 5 designates generally a conventional form of spark plug equipped with a main electrode 6 that is of a length to extend considerably above the upper end of the plug porcelain so as to threadedly receive 45 the usual binding nut 7, said electrode obviously being threaded.

In carrying out the present invention, I

provide an electrode wherein the upper end thereof is provided with a reduced and unthreaded extension 8 for receiving a head 9 of any suitable design, preferably of the inverted conical shape as disclosed, said head being obviously provided with a vertical bore 10 for receiving the extension 8 of said electrode 6. After the disposition of said head 9 upon the extension 8 the end of the extension is flattened as at 11 so as to prevent the detachment of the head from the extension. 50

Obviously the binding nut 7 may be turned upwardly upon the electrode 6 a sufficient distance to enable the conducting wire to be attached to the electrode beneath said nut, but by reason of the head 9 the nut will be prevented from entire removal from the electrode usually resulting in the loss of the 55 same.

Having thus described the invention, what I claim as new is:—

In a spark plug of the class described, a main threaded electrode extending beyond 70 the upper end of the plug porcelain, a binding nut threaded on the projecting end of the electrode, an unthreaded reduced extension pin formed on the upper end of the electrode, a head arranged on the reduced unthreaded extension pin, the bottom of said head engaging the shoulder formed at the juncture of the electrode with the extension pin, the upper end of the pin being flattened, and engaging the upper end of the 75 head to permanently secure the head on the pin, the top of the binding nut being normally spaced from the bottom of the head to permit said binding nut to move upwardly whereby to permit a conductor wire to be 80 attached to the electrode and held thereon when the binding nut is turned downwardly, said head providing an abutment to limit the upward movement of the binding nut and prevent the displacement of the same 85 from the threaded end of the electrode.

In testimony whereof I affix my signature.

ERWIN H. EILER.
